(57) **CLAIM**

The ornamental design for a hair clipper, as shown and described.

DESCRIPTION

FIG. 1 is a top rear perspective view of the present hair clipper;

FIG. 2 is a left side view of the hair clipper of FIG. 1;

FIG. 3 is a right side view of the present hair clipper;

FIG. 4 is a front view of the hair clipper of FIG. 1;

FIG. 5 is a rear view of the hair clipper of FIG. 1;

FIG. 6 is a top plan view of the present hair clipper; and,

FIG. 7 is a bottom plan view of the hair clipper of FIG. 1. The structure shown in broken lines depicts portions of the present hair clipper that do not form part of the claimed invention.

1 Claim, 4 Drawing Sheets
